(57) CLAIM

The ornamental design for a portion of a shoe upper, as shown and described.

DESCRIPTION

FIG. 1 is a perspective view of a portion of a shoe upper showing our new design;

FIG. 2 is a side elevational view of the medial side thereof;

FIG. 3 is a side elevational view of the lateral side thereof;

FIG. 4 is a front view thereof;

FIG. 5 is a rear view thereof; and,

FIG. 6 is a top view thereof.

The uneven broken lines immediately adjacent to the shaded portions of the design represent an unclaimed boundary of the design. The uneven broken lines and unshaded regions are for illustrative purposes only and form no part of the claimed design.
